UNITED STATES PATENT OFFICE.

HARRY M. DENYES, OF SAGINAW, MICHIGAN.

DESIGN FOR A COMBINED SPARK AND THROTTLE CONTROL.

Application filed October 1, 1924. Serial No. 10,932. Term of patent 14 years.

To all whom it may concern:

Be it known that I, HARRY M. DENYES, a citizen of the United States, and a resident of Saginaw, county of Saginaw and State of Michigan, have invented a new, original, and ornamental Design for Combined Spark and Throttle Control, of which the following is a specification, reference being made to the accompanying drawing, forming a part thereof.

In the drawings, the figure is a perspective view of spark and throttle controls and horn button, showing my new design.

I claim:

The ornamental design for a combined spark and throttle control as shown.

HARRY M. DENYES.
